EDWARD S. MARKS, OF SYRACUSE, NEW YORK, ASSIGNOR, BY MESNE ASSIGNMENTS, TO FRANKLIN DEVELOPMENT CORPORATION, OF SYRACUSE, NEW YORK, A CORPORATION OF NEW YORK

CRANK CASE VENTILATOR

Application filed September 26, 1928. Serial No. 308,517.

This invention has for its object, a particularly simple and efficient means for ventilating the crank case of an internal combustion engine, which ventilating means is controlled by the temperature of the crank case.

5 The invention is based upon the fact that when the crank case interior and the oil in the engine base is cold, a considerable blast of air is necessary to expel the vapors which blow by the piston rings of the engine before these vapors condense in the base and otherwise affect the crank case oil and that after 10 the engine and the oil has become heated to a predetermined temperature, not as much ventilation is required and hence, in some cases the continuing of the blast of air into the crank case combined with the heated oil, builds up a pressure whereby the oil blows 15 out of the breather pipe and causes high oil consumption.

20 The invention comprises primarily the overcoming of these difficulties by thermostatically controlling the amount of air necessary when the crank case or engine base is cold to expel the vapors and to cut down or discontinue the air blast when the engine or the oil heats up.

25 The invention consists in the novel features and in the combinations and constructions hereinafter set forth and claimed.

30 In describing this invention, reference is had to the accompanying drawings, in which like characters designate corresponding parts in all the views.

35 Figure 1 is a side elevation of an internal combustion engine embodying my invention wherein this invention is shown as applied to a Franklin air cooled engine.

40 Figure 2 is an enlarged fragmentary sectional view illustrating the air filter and the thermostatically controlled valve in the crank case of the engine.

45 This invention comprises generally means for passing a current of air into the crank case of an internal combustion engine through an inlet in the crank case located remote from the outlet or breather, and a thermostatically operated valve for controlling the flow of air through the inlet, the valve being usually normally open to permit a full flow of

air through the inlet and operable as the temperature of the oil or crank case rises to close the inlet more or less.

I have here illustrated my invention as embodied in an air cooled engine of the 55 Franklin type.

In the drawings, 1 designates the crank case having an air inlet at 2 at its front end and an outlet or breather pipe 3 at its rear end.

4 designates the cylinders having jackets 5 through which a cooling current of air is 60 passed.

6 is an air conduit extending over the heads of the cylinders and communicating with the jackets 5 and also communicating at its front end with the upper end of a fan casing 7 having a fan rotor 8 therein, this being mounted upon the front end of the crank shaft of the engine.

When the engine is running, the impeller 70 or rotor 8 blows the air from the fan casing 7, conduit 6 and downwardly over the cylinders 4 through the jackets 5.

75 Preferably, the air for ventilating the crank case is taken from the cooling system and consists of a conduit 9 connecting the upper or discharge end of the fan casing with the inlet 2 of the crank case. Preferably, an air cleaner is embodied in the conduit 9, this air cleaner comprising an enlarged closed cylindrical casing 10 connected at its upper end to one section 11 of the conduit 9 and at its other end to the section 12 of the conduit, which section 12 leads into the crank case.

80 The air cleaner further includes a cylindrical screen or sleeve 13 mounted in the casing 10 and spaced apart from the cylindrical walls thereof and from the top wall of the casing and being secured to the bottom of the casing in communication with the conduit section 12. A sleeve 14 of straining material, preferably flannel encloses the screen 13 and covers the open top of the screen 13. The lower end of the screen 13 is shown as 85 fitted over a nipple 15 on the bottom of the casing 10 and fixed thereto as by soldering and the lower end of the flannel screen 14 is 90 deflected outwardly or formed with an annular flange 16 and the parts are held in position 95 by soldering.

sition as by screws 18 extending through the bottom of the casing 10 and said flange 16. Usually, an annular gasket 19 overlies the flange and the heads of the screws bear 5 against the gasket. Preferably, the bottom of the casing and the cylindrical portion thereof are detachably connected in any suitable manner as by bayonet joints and also, the casing 10 or the cylindrical part thereof 10 is detachably secured to the section 11 of the conduit 9 by a clamp 20 so that the cylindrical part of the casing 10 can be readily removed for giving access to the interior thereof.

15. 21 is a coupling mounted in the wall of the crank case, it being here shown as having a nipple threading into the wall of the crank case and as also being threaded at 22 at its outer end for receiving a collar 23, which 20 couples the section 12 of the conduit thereto. The inlet passage 2 is formed in this coupling 21. The thermostatic valve is carried by the coupling 21 and projects into the crank case and comprises a semi-tubular member 24 open 25 along one side and having a wall 25 at its inner end which closes the semi-tubular member at its inner end, and a thermostat in the form of a flat reed 26 extending lengthwise of the semi-tubular member 24 along the 30 open side thereof, the thermostat or reed 26 being fixed at 27 at one end and having its other end free so as to flex under changes of temperature and hence, close the open side of the member 24 more or less.

35. The thermostatic member 26 is normally separated from the open side of the semi-tubular member 24, that is, it is separated when the engine is cold, so that a current of air will pass into the crank case when the engine is cold and carry any vapors therein out 40 through the breather pipe. As the engine heats up, the reed or member 26 under the influence of the heat, closes the open side of the semi-tubular member 24 more or less and hence, cuts off the blast of air.

45. This thermostatically controlled valve for crank case ventilators is particularly advantageous in that when the interior of the crank case or the oil therein is cold, a considerable 50 blast of air passes through the crank case to expel the vapors which blow by the piston rings before the vapors condense, and in that after the engine has become heated so that the vapors do not form to any great extent 55 and hence, but little ventilation is required, the blast of air is cut down more or less or entirely cut off and hence, lubricating oil vapors or lubricating oil in suspension in the air does not blow out through the breather 60 pipe.

What I claim is:

1. An internal combustion engine, the crank case of which is provided with an air inlet and an air outlet both located above the 65 level of the oil therein and means for pass-

ing a current of air through the inlet, in combination with a thermostatically operated valve for controlling the passage of air through the inlet.

2. An internal combustion engine, the 70 crank case of which is provided with an air inlet and an air outlet both located above the level of the oil therein and means for passing a current of air into the crank case through the inlet, in combination with a thermo-operated valve controlled by the temperature of the crank case for controlling the flow of air through the inlet.

3. An internal combustion engine, the 80 crank case of which is provided with an air inlet and an air outlet both located above the level of the oil therein and means for passing a current of air into the crank case through the inlet, in combination with a normally 85 open thermo-operated valve controlled by the temperature of the crank case for controlling the flow of air into the crank case through said inlet.

4. An internal combustion engine having 90 its crank case provided with an air inlet and an air outlet both located above the level of the oil therein and means for passing a current of air through the inlet, in combination with a normally open thermostatically 95 operated valve mounted in the wall of the crank case to be subject to the temperature of the crank case for controlling the passing of air through the inlet.

5. In an internal combustion engine having 100 its crank case provided with an air inlet and an air outlet both located above the level of the oil therein, the combination of a normally open thermostatically closable valve in the inlet and means for blowing air through the 105 inlet including a conduit and an air filter in the conduit.

6. In an internal combustion engine having 110 an air cooling system, a fan for creating a cooling current of air around the engine; an air conduit associated with said cooling 115 system and connected with the engine crank case, at a point above the oil level therein, for passing a portion of the air current to the crank case; an air outlet from the crank case at a point above the oil level therein; and a thermostatically operated valve for controlling the flow of air through the crank case.

In testimony whereof, I have hereunto 120 signed my name, at Syracuse, in the county of Onondaga, and in the State of New York, this 14th day of September, 1928.

EDWARD S. MARKS.
